E. F. W. ALEXANDERSON,
METHOD OF AND MEANS FOR CONTROLLING HIGH FREQUENCY ALTERNATING CURRENTS.
APPLICATION FILED JAN. 21, 1916.

1,328,610.

Patented Jan. 20, 1920.

UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

METHOD OF AND MEANS FOR CONTROLLING HIGH-FREQUENCY ALTERNATING CURRENTS.

1,328,610.

Specification of Letters Patent.

Patented Jan. 20, 1920.

Application filed January 21, 1918. Serial No. 73,443.

To all whom it may concern:

Be it known that I, ERNST F. W. ALEXANDERSON, a citizen of the United States, residing at Schenectady, in the county of Schenectady, State of New York, have invented certain new and useful Improvements in Methods of and Means for Controlling High-Frequency Alternating Currents, of which the following is a specification.

- 10 My present invention relates to improvements in apparatus for controlling alternating electric currents, and more especially for controlling alternating currents used in wireless signaling systems.
- 15 The object of my invention is to provide means for efficiently controlling and varying the amplitude of a high frequency current flowing in a signaling circuit in accordance with variations in the amplitude of a signaling current of much lower frequency and amplitude.

In carrying my invention into effect I make use of electromagnetic apparatus of a kind which I term magnetic amplifiers, such, 25 for example, as are described in my U. S. Patent No. 1,206,643. By varying the circuit arrangements used in adapting a magnetic amplifier to a signaling system over those which have heretofore been employed, 30 and by using in conjunction therewith suitable condensers in a way which will be more fully set forth in the description which follows, I am able to accomplish the object of my invention.

35 The novel features which I believe to be characteristic of my invention are pointed out with particularity in the appended claims. The invention itself, however, with further objects and advantages will best be 40 understood by reference to the following description taken in connection with the accompanying drawing in which Figure 1 is a simple diagrammatic representation of the apparatus and circuit connections which may 45 be employed in carrying my invention into effect; Fig. 2 shows diagrammatically the preferred form of magnetic amplifier used with the arrangement of the magnetizing winding thereon; Fig. 3 is a graphic representation of the volt ampere characteristics 50 of the amplifier under different conditions of operation; Fig. 4 shows the combined volt ampere characteristics of a high frequency

alternator and of a magnetic amplifier with different values of control current; Fig. 5 55 is a diagrammatic representation of a modification in the apparatus and circuit connections which may be used and Fig. 6 is a diagram showing how the system of Fig. 1 may be modified so that it may be used for 60 telegraphy instead of telephony.

As indicated in Fig. 1, the armature winding 1 of a high frequency alternator, the rotor 2 of which is driven by a motor 3, is inductively connected by means of the transformer 4 with the antenna 5. Coils 6 and 7 of a magnetic amplifier are connected in shunt to the secondary of transformer 4 and in parallel to each other. A variable condenser 8 is connected in series with both coils 70 and condensers 9 and 10 are connected in series with coils 6 and 7 respectively. A condenser 11 may also be connected in shunt to the two coils. By varying the current flowing through coils 6 and 7, the electro-motive force at the terminals of the secondary of transformer 4 may be varied and the amplitude of the current flowing in the antenna will be varied accordingly. The means for varying the current flow in coils 80 6 and 7 comprises two controlling coils 12 and 13. Coil 12 is supplied with a constant direct current from the source 14 and the value of this current required to give the magnetic circuit of the amplifier a desired 85 degree of saturation may be adjusted by the variable resistance 15. The winding 13 is supplied with the signaling current which in the present example is furnished by the secondary of transformer 16, the primary 90 circuit of which includes a telephone transmitter 17 with the usual local battery 18. A high inductance 19 is preferably inserted in the circuit of coil 12 in order that this circuit shall offer a high impedance to the 95 flow of currents induced therein from the coil 13. It is also desirable that the circuit of coil 13 shall be resonant to the most common frequency of the current in that circuit and for this purpose a variable condenser 20 100 in series with the circuit may be employed. This condenser will preferably be shunted by resistance 21 in order that the circuit shall not be too highly resonant.

By the organization which I have thus described it is possible by means of the small

energy variations which are produced in the telephone circuit by varying the resistance of transmitter 17 to produce much larger variations in the energy radiated from the 5 antenna. In my copending application, Serial No. 63,438, filed November 26, 1915, I have shown that it is theoretically possible with apparatus such as I employ to produce an amplification of the current variations in 10 the telephone transmitter having a ratio equal to the ratio between the frequency of the high frequency current flowing in coils 6 and 7, and that of the current which is to be amplified. While the system here shown 15 is especially adapted for wireless telephony, it may, by suitable modification, equally well be employed for transmitting telegraphic signals.

One manner in which this may be accomplished is indicated in Fig. 6 in which the 20 coil 13 is included in the circuit with a telegraph key 31 and battery 32.

In Fig. 2, I have shown a magnetic structure which is especially suitable for a magnetic amplifier. In this case two magnetic cores 22 and 23 carry the coils 6 and 7. The windings are so arranged that the flux produced by the high frequency current in the coils is in opposite directions in the two 30 cores and as a result this flux is confined to the two cores and the small portions 24 of the structure adjacent the cores. The winding 25 which carries the controlling current is wound around both of the cores as indicated. The flux produced by this winding traverses the two cores in the same direction and also traverses the outer legs 26 of the magnetic structure. It will be apparent that each turn of the controlling winding 40 is threaded by the flux in the cores 22 and 23 in opposite directions so that any electromotive forces induced in the winding by the high frequency flux are neutralized in each turn. While I have shown a single controlling winding this may be divided into two 45 separate parts as indicated in Fig. 1.

Magnetic amplifiers of the type which I employ may be operated by two distinct methods. In case the two high frequency 50 coils are connected in series, as shown in my U. S. Patent #1,206,643, the current in those coils is forced to be equal at any moment and the resulting flux is allowed to adjust itself in accordance with the permeability of the iron so that the voltage appearing 55 at the terminals of the high frequency winding becomes a variable function depending upon the current distribution. In case the two coils are connected in multiple 60 as I have indicated in Fig. 1, the relation of the currents in the two coils is indefinite but the flux variation in the two branches of the core is forced to be equal. In Fig. 3, curve A shows the volt ampere characteristic of the coils with the first method of op-

eration and curve B shows the characteristic with the second method of operation. These curves are obtained from tests with both methods of operation with the same constant value of control excitation in both 70 cases. These curves show that the volt ampere characteristic with multiple connection has a lower curvature than the one with the series connection and corresponds to lower impedance. The multiple connection 75 is therefore more advantageous since lower impedance with a definite control excitation means greater sensitiveness and a lower curvature means that larger currents can be carried without causing instability, as will 80 be explained later.

With the multiple connection the flux variations are forced by the circulating current flowing in the short-circuit between the two multiple coils. The induced current in 85 this short circuit tends to oppose any changes in the average flux and thus a telephone current in the control winding would simply cause a corresponding short circuit between the two high frequency coils without producing the desired flux variations. This difficulty, however, can be overcome by taking advantage of the fact that the high frequency winding needs to operate only at 90 radio frequencies which are very much higher than the frequency of the telephone current. It is, therefore, possible to find a value for the condensers 9 and 10, such that this circuit acts as a short circuit for the radio currents and practically as an open 100 circuit for the telephone current.

The current in the high frequency winding has a tendency to depress the average flux for the reason that the flux decreases more rapidly when high frequency current 105 is opposed to the control excitation than it increases when the high frequency current is added to the control excitation. The result is that the greater the current in the high frequency winding, the lower is the 110 average flux of the high frequency coil although the control excitation is kept constant. It has also been shown above that the degree to which the short circuit opposes 115 changes in the average flux can be modified by the introduction of suitable condensers.

In order to show how by other modifications the magnetic amplifier may be utilized to advantage for controlling the voltage of an alternator, reference may be had to the 120 alternator characteristics shown in Fig. 4. The alternator voltage is plotted against the current in the shunt circuit and curves G, G' and G'' represent the alternator characteristic for different outputs. The magnetic 125 amplifier is used in the control shunt circuit and the volt ampere characteristics of the amplifier with different degrees of excitation are shown in the curves H, H', H'', etc., curve H being the characteristic with no ex- 130

citation in the controlling winding. The intersections between the sets of curves give the alternator voltages at the corresponding amplifier excitations. These curves show 5 that the alternator voltage approaches zero as the amplifier excitation increases and it is possible to obtain effective control of telegraphy in this way without exceeding the current carrying capacity of the control 10 winding of the amplifier. However, these results are not all that is to be desired for telephony because there is a lack of linear proportionality between the alternator voltage and amplifier control current. The improvements 15 in the characteristics of the amplifier that are described have the effect not only of securing this linear proportionality but also a much higher degree of sensitivity. The nature of these improvements 20 can be explained by further reference to the volt ampere characteristics. These characteristics are a set of curves radiating from the origin, each of which represents a certain control excitation. For the complete 25 control of the alternator, to vary its voltage from zero to a maximum, it would be desirable that the first curve should coincide with the Y-axis and the last coincide with the X-axis, and that the other curves 30 should be distributed uniformly between these limits. Instead of this, however, the amplifier characteristics all fall within a certain angle covering only a little more than one-half the desired sweep. This disadvantage 35 may be overcome to a large extent by neutralizing part of the voltage of the amplifier winding by a suitable series condenser 8 so that the circuit becomes resonant when the radiation from the antenna is a minimum and neutralizing part of the current by a suitable shunt condenser 11 so that the circuit which includes the coils and the shunt condenser become resonant when the radiation from the antenna is a maximum. If the condenser is chosen so that it 40 exactly neutralizes the inductance of the amplifier winding at some definite value of excitation, the resulting impedance at this excitation becomes a minimum and the impedance 45 at any lower excitation is determined by the difference between the inductive reactance of the amplifier coil and the capacity reactance of the series condenser. The smaller this difference, the lower will be the amplifier excitation which gives 50 minimum impedance and the corresponding minimum of alternator voltage. This means that the sensitiveness of the amplifier is increased because a smaller excitation 55 is needed to reduce the alternator voltage. The increase of sensitiveness which can be obtained in this way is, however not unlimited. If the minimum impedance 60 is obtained as a result of a large inductive and a large capacity reactance, the core 65 loss due to hysteresis and eddy currents becomes appreciable and appears as an equivalent resistance which cannot be neutralized. The application of a series condenser in this way is shown and described 70 in my prior application, Serial No. 873,110, filed November 20, 1914.

The voltage which results from the combination alternator and amplifier can be determined by the intersection of the alternator and amplifier characteristics. When these curves have a definite sharp intersection point, a definite alternator voltage results from each excitation of the amplifier. If on the other hand the curves have such 75 a shape that the alternator and amplifier characteristic curves become parallel or tangent in some place, the intersection becomes indefinite and the result is instability and generation of self-excited oscillations. 80 The conditions which lead to the instability may be illustrated by the curves shown in broken lines in Fig. 4. If a series condenser is used which has such a value that it has the voltage characteristic indicated by the 85 curve C, the resultant characteristic of the shunt circuit for different values of excitation will be represented by the difference between this curve and the curves H, H', etc. For example, curve H will be brought 90 down so that it occupies a position H₁ and curve H'''' will be practically coincident with the X-axis. All of the new characteristics will have definite intersection points with the generator characteristics and the 95 operation will, therefore, be stable under all conditions of load which are indicated. If, however, a condenser is used which is of such capacity that it has the voltage characteristic indicated by the curve C', the 100 resultant of curve H with this condenser curve will be the curve H₂. It will be seen that this curve becomes tangent to the generator characteristic G and, therefore, operation with this generator output and this 105 particular value of excitation will be unstable. With higher degrees of excitation, it will be apparent that the point of instability will be reached with lower generator 110 outputs.

In Fig. 5 I have shown an arrangement which is the equivalent of that shown in Fig. 1, only in this case a separate winding 115 27 on the high frequency alternator supplies current for the operation of a second amplifier 28. The circuit through the coils of this amplifier is controlled in the same manner as the current in the amplifier coils in the organization shown in Fig. 1. The variable high frequency current thus produced in the 120 secondary of transformer 29 is rectified by rectifier 30 and supplied to the controlling winding 13 of the first amplifier as a pulsating unidirectional current. While I have indicated but one controlling winding in 130

this case a second winding may be employed if desired to furnish a constant magnetization of the core as in the arrangement shown in Fig. 1. This constant direct current may 5 also if desired be supplied to the same winding that carries the variable current as indicated in the supply connections for the controlling winding 31 of amplifier 28.

What I claim as new and desire to secure 10 by Letters Patent of the United States is:

1. The combination in a wireless signaling system of an antenna, a source of high frequency alternating current connected to said antenna, an electromagnetic device 15 comprising a pair of windings connected in shunt to each other and included in a circuit with said high frequency source, a pair of parallel cores magnetized by said windings in such a way that the flux produced 20 therein flows in opposite directions in said cores, a controlling winding surrounding said high frequency windings so as to produce a flux in the same direction through both of said cores, means for supplying said 25 controlling winding with a variable current, the variations of which are of comparatively low frequency in comparison with the frequency of the current in the high frequency circuit, a condenser in series with said high 30 frequency winding to neutralize part of the voltage of said windings, a condenser in shunt with said high frequency windings for neutralizing a part of the current therein, and condensers in the closed circuit 35 formed by the high frequency windings of such capacity that the circuit offers a low impedance to high frequency currents but a high impedance to currents of the frequency of the controlling current.

40 2. The combination in a wireless signaling system of an antenna, a source of high frequency alternating current connected to said antenna, an electromagnetic device comprising a pair of windings connected in 45 shunt to each other and included in a circuit with said high frequency source, a pair of parallel cores magnetized by said windings in such a way that the flux produced therein flows in opposite directions in said cores,

50 a controlling winding surrounding said high frequency windings so as to produce a flux in the same direction through both of said cores, means for supplying said controlling winding with a variable current, the variations of which are of comparatively low frequency in comparison with the frequency of the current in the high frequency circuit, a condenser in series with said high frequency windings to neutralize part of the 55 voltage of said windings and a condenser in shunt to said high frequency windings for neutralizing part of the current therein.

60 3. The combination in a wireless signaling system of an antenna, a source of high frequency alternating current connected to

said antenna, an electromagnetic device comprising a pair of windings connected in shunt to each other and included in a circuit with said high frequency source, a pair of parallel cores magnetized by said windings 70 in such a way that the flux produced therein flows in opposite directions in said cores, a controlling winding surrounding said high frequency windings so as to produce a flux in the same direction through both of said cores, means for supplying said controlling winding with a variable current, the variations of which are of comparatively low frequency in comparison with the frequency of the current in the high frequency circuit, a 75 condenser in series with said high frequency windings to neutralize part of the voltage of said windings and condensers in a closed circuit formed by the high frequency windings of such capacity that the circuit offers 80 a low impedance to high frequency currents but a high impedance to currents of the frequency of the controlling current.

4. The combination in a wireless signaling system of an antenna, a source of high 90 frequency alternating current connected to said antenna, an electromagnetic device comprising a pair of windings connected in shunt to each other and included in a circuit with said high frequency source, a pair of parallel cores magnetized by said windings in such a way that the flux produced 95 therein flows in opposite directions in said cores, a controlling winding surrounding said high frequency windings so as to produce a flux in the same direction through both of said cores, means for supplying said controlling winding with a variable current, the variations of which are of comparatively low frequency in comparison with the frequency of the current in the high frequency circuit, a condenser in shunt to said high frequency windings for 100 neutralizing a part of the current therein, and condensers in a closed circuit formed by the high frequency windings of such capacity that the circuit offers a low impedance to high frequency currents and a high impedance to currents of the frequency of the controlling current.

110 5. The combination in a wireless signaling system of an antenna, a source of high frequency alternating current connected to said antenna, an electromagnetic device comprising a pair of windings connected in 120 shunt to each other and included in a circuit with said high frequency source, a pair of parallel cores magnetized by said windings in such a way that the flux produced therein flows in opposite directions in said cores, a controlling winding surrounding said high frequency windings so as to produce a flux in the same direction through 125 both of said cores, means for supplying said controlling winding with a variable cur-

rent, the variations of which are of comparatively low frequency in comparison with the frequency of the current in the high frequency circuit, and a condenser in 5 series with said high frequency winding to neutralize part of the voltage of said windings.

6. The combination in a wireless signaling system of an antenna, a source of high 10 frequency alternating current connected to said antenna, an electromagnetic device comprising a pair of windings connected in shunt to each other and included in a circuit with said high frequency source, a pair 15 of parallel cores magnetized by said windings in such a way that the flux produced therein flows in opposite directions in said cores, a controlling winding surrounding said high frequency windings so as to produce a flux in the same direction through 20 both of said cores, means for supplying said controlling winding with a variable current, the variations of which are of comparatively low frequency in comparison 25 with the frequency of the current in the high frequency circuit, and a condenser in shunt with said high frequency windings for neutralizing a part of the current therein.

30 7. The combination in a wireless signaling system of an antenna, a source of high frequency alternating current connected to said antenna, an electromagnetic device comprising a pair of windings connected in 35 shunt to each other and included in a circuit with said high frequency source, a pair of parallel cores magnetized by said windings in such a way that the flux produced therein flows in opposite directions in said 40 cores, a controlling winding surrounding said high frequency windings so as to produce a flux in the same direction through both of said cores, means for supplying said controlling winding with a variable current, the variations of which are of comparatively 45 low frequency in comparison with the frequency of the current in the high frequency circuit, and condensers in a closed circuit formed by the high frequency 50 windings of such capacity that the circuit offers a low impedance to high frequency currents but a high impedance to currents of the frequency of the controlling current.

55 8. The combination in a wireless signaling system of an antenna, a source of high frequency alternating current connected to said antenna, an electromagnetic device comprising windings included in shunt to each 60 other in a circuit with said high frequency source and a condenser in series with said windings to neutralize part of the voltage of said windings.

65 9. The combination in a wireless signaling system of an antenna circuit, a source

of high frequency alternating current connected to said antenna circuit, an electromagnetic device comprising a pair of windings connected in shunt to each other and included in a shunt circuit to the antenna 70 circuit, and means for controlling the magnetization of said device in accordance with variations in a controlling current.

10. The combination in a wireless signaling system of an antenna, a source of high 75 frequency alternating current connected to said antenna, an electromagnetic device comprising a pair of windings included in shunt to each other in a circuit with said high frequency source, a condenser in series 80 with said high frequency windings to neutralize part of the voltage of said windings, and a condenser in shunt with said high frequency windings for neutralizing part 85 of the current therein.

11. An electromagnetic device for controlling the flow in an electric circuit of high frequency current comprising a pair of windings connected in shunt to each other and included in the high frequency circuit, 90 a condenser in series with said high frequency windings to neutralize part of the voltage of said windings, and a condenser in shunt with said high frequency windings for neutralizing part 95 of the current therein.

12. Means for controlling the flow of high frequency current in an electric circuit comprising an electromagnetic device having a pair of windings connected in shunt to each other and included in the high frequency circuit, a pair of parallel cores magnetized by said windings in such a way that the flux produced therein flows in opposite directions in said cores, a controlling winding surrounding said high frequency windings so as to produce a flux in the same direction through both of said cores, means for supplying said controlling winding with the controlling current and a condenser in series 100 with said high frequency windings to neutralize part of the voltage of said windings.

13. Means for amplifying a variable current comprising a source of alternating current, the frequency of which is high in comparison with the frequency of the variations in the current to be amplified, an electromagnetic device comprising a pair of windings connected in shunt to each other and included in the circuit of the high frequency 110 current, a pair of parallel cores magnetized by said windings in such a way that the flux produced therein flows in opposite directions in said cores, a controlling winding surrounding said high frequency windings 115 so as to produce a flux in the same direction through both of said cores, means for supplying the variable current which is to be amplified to said controlling winding, and condensers in a closed circuit formed 120

125

130

by said high frequency windings of such capacity that the circuit offers a low impedance to high frequency currents but a high impedance to currents of the frequency 5 of the current which is to be amplified.

14. The method of controlling the flow in an electric circuit of a high frequency alternating current which consists in causing the current to flow through a pair of 10 windings surrounding a pair of magnetic cores, varying the magnetic flux in said cores to vary the inductance of the circuit and neutralizing a part of the voltage of said windings.

15. 15. The method of controlling the flow in an electric circuit of a high frequency alternating current which consists in continuously varying the tuning of an auxiliary circuit supplied with energy from said electric 20 circuit in such a way that it reaches a state of resonance when the output of the main circuit is a minimum.

16. The method of controlling the flow in an electric circuit of a high frequency alternating current which consists in continuously varying the inductance of an auxiliary circuit by varying the magnetic permeability of the circuit and neutralizing part of the inductance by electrostatic capacity so that 30 the auxiliary circuit reaches a state of resonance when the output of the main circuit is a minimum.

17. The method of controlling the flow in an electric circuit of a high frequency alternating current which comprises varying an inductance included in two auxiliary circuits associated with the main circuit and neutralizing a part of the inductance by electrostatic capacities in both of the 40 auxiliary circuits in such a way that one of the auxiliary circuits reaches a state of resonance when the output of the main circuit is a minimum and the other reaches a state of resonance when the output of the 45 main circuit is a maximum.

18. The method of controlling the flow in an electric circuit of a high frequency alternating current which comprises tuning differentially two auxiliary circuits associated with the main circuit in such a way that one of the auxiliary circuits reaches a state of resonance when the output of the main circuit is a minimum and the other reaches a state of resonance when the output 55 of the main circuit is a maximum.

19. The combination in a wireless signaling system of an antenna circuit supplied by a source of high frequency alternating current, a reactance and a variable condenser 60 connected in shunt to said high frequency source and to said antenna circuit, a second circuit including a magnetizing winding inductively related to said reactance in such a manner that the impedance of the antenna 65 circuit may be varied by varying the cur-

rent flowing in said magnetizing winding, and means for causing a variable current to flow in said second circuit.

20. Means for controlling the flow of a radio frequency alternating current in an 70 electric circuit comprising a pair of magnetic cores, a pair of windings for magnetizing said cores which are connected in shunt to each other and supplied with current from said circuit, means for producing a low frequency controlling flux in said cores in such a way that at any given instant the controlling flux and the radio frequency flux are in the same direction in one core and in opposite directions in the other core, a 75 80 condenser in series with said windings for neutralizing a part of the voltage of said windings and condensers in the closed circuit formed by said windings of such capacity that the circuit offers a low impedance to 85 radio frequency currents but a high impedance to currents of the frequency of the controlling flux.

21. Means for controlling the flow of a radio frequency alternating current in an 90 electric circuit comprising a pair of magnetic cores, a pair of windings magnetizing said cores which are connected in shunt to each other and supplied with current from said circuit, means for producing a low 95 frequency controlling flux in said cores in such a way that at any given instant the controlling flux and the radio frequency flux are in the same direction in one core and in opposite directions in the other core, and a 100 104 condenser in series with said windings for neutralizing part of the voltage of said windings.

22. Means for controlling the flow of a radio frequency alternating current in an 105 electric circuit comprising a pair of magnetic cores, a pair of windings for magnetizing said cores which are connected in shunt to each other and supplied with current from said circuit, means for producing a 110 low frequency controlling flux in said cores in such a way that at any given instant the controlling flux and the radio frequency flux are in the same direction in one core and in opposite directions in the other core, and 115 condensers in the closed circuit formed by said windings of such capacity that the circuit offers a low impedance to high frequency currents but a high impedance to 120 currents of the frequency of the controlling flux.

23. Means for controlling the flow of a radio frequency alternating current in an electric circuit comprising a pair of magnetic cores, a pair of windings for magnetizing said cores which are connected in shunt to each other and supplied with current from said circuit, means for producing a low frequency controlling flux in said cores in such a way that at any given instant the 125 130

controlling flux and the radio frequency flux are in the same direction in one core and in opposite directions in the other core, and a condenser in series with said windings for neutralizing part of the voltage of said windings, the closed circuit formed by said windings being so arranged that it offers a low impedance to the radio frequency currents and a high impedance to currents of the frequency of the controlling flux.

24. Means for amplifying a variable current comprising a source of alternating current the frequency of which is high in comparison with the frequency of the variations in the current to be amplified, a pair of magnetic cores, a pair of windings for magnetizing said cores which are connected in shunt with each other and supplied from said source of alternating current, means for producing by the current to be amplified a flux in said cores in such a way that at any given instant, the flux produced by the variable current and the high frequency flux are in the same direction in one core and in opposite directions in the other core, and condensers in the closed circuit formed by said windings of such capacity that the circuit offers a low impedance to high frequency currents but a high impedance to the currents of the frequency of the current which is to be amplified.

25. The combination in a wireless signaling system of an antenna, a source of radio frequency alternating current connected to said antenna, a pair of magnetic cores, a pair of windings for magnetizing said cores which are connected in shunt to each other and included in a shunt circuit to the antenna circuit, means for producing a low frequency controlling flux in said cores in such a way that at any given instant the controlling flux and the radio frequency flux are in the same direction in one core and in opposite directions in the other core, means for neutralizing a part of the voltage of said windings and condensers in the closed circuit formed by said windings of such capacity that the circuit offers a low impedance to radio frequency currents but a high impedance to currents of the frequency of the controlling flux.

26. Means for controlling the flow of radio frequency current in an electric circuit comprising a variable inductance having a shunt and a series capacity associated therewith, the capacities being so chosen that at one value of the inductance it is neutralized by the series capacity at a desired frequency and at a second value of the inductance it is neutralized by the shunt capacity at the same frequency, and means for varying the inductance between said two values.

27. Means for controlling the flow of radio frequency current in an electric circuit comprising a variable inductance having a shunt and a series capacity associated therewith, the capacities being so chosen that at one value of the inductance it is neutralized by the series capacity at a desired frequency and at a second value of the inductance it is neutralized by the shunt capacity at the same frequency.

28. A radio signaling system comprising an antenna which is resonant to a desired frequency supplied by a source of radio frequency continuous current and having associated therewith a secondary circuit which comprises a variable inductance and a series capacity and a third circuit which comprises the variable inductance and a shunt capacity, the second circuit being so proportioned that it becomes resonant to the desired frequency at one value of the variable inductance and the third circuit being so proportioned that it becomes resonant to the desired frequency at a second value of the variable inductance.

29. The method of operating a radiating antenna system which comprises a variable inductance which is common to two oscillating circuits which consists in varying the value of said inductance in such a way that under one condition of operation one of the oscillating circuits becomes resonant to a desired frequency and under another condition of operation the other oscillating circuit becomes resonant to the desired frequency.

In witness whereof I have set my hand this 20th January, 1916.

ERNST F. W. ALEXANDERSON.
